Filed Sept. 13, 1963, Ser. No. 308,791

6 Claims. (Cl. 103—103)

The present invention relates to centrifugal pumps and, more particularly, to improvements in centrifugal pumps which are useful in connection with the pumping of liquids having solids mechanically entrained therein, sewage and slurries being examples.

In the past a great many types of centrifugal pumps have been designed to function in various contexts. Those centrifugal pumps of which the inventor is aware appear to be deficient in certain respects, however, wherein intended usage is that of pumping liquids having mechanically entrained solids, such as sewage and slurry liquids. Present centrifugal pump designs, when used in such contexts, appear to have disadvantages in undesired flow characteristics, in impeller vane wear and, indeed, in clogging the impeller with such stringy material as may be present in the liquid, in the course of pumping operation. In connection with the latter objection, conventional pumps require a large clean-out port, not needed in the present invention, which clean-out port in conventional designs is proximate the impeller and is necessitated for cleaning the impeller area. Further, present designs of impeller vanes themselves have been such that, heretofore, they have been positioned at a direct or proximate impact area so that hard, solid granules will directly impinge upon the leading edges of the blade and cause the latter to become subject to excessive wear in a short time. Furthermore, present vane designs for conventional pump impellers provide reduced passage for the liquid being pumped and offer excessive obstruction areas which tend to impede complete flow.

Accordingly, a principal object of the invention is to provide a new and improved centrifugal pump wherein the impeller thereof provides increased throat or passageway from the inlet orifice along and adjacent the impeller to the outlet orifice of the pump.

A further object of the invention is to provide in a centrifugal pump an improved impeller having a front face of general convex character, the front face serving to reduce turbulence thereof, thereby increasing pumping efficiency, and, further, permitting solid objects impinging thereon to advance outwardly in the most optimal manner.

A further object of the invention is to provide in a centrifugal pump an impeller having a convex front face wherein a central portion of the face is free of vane protrusions, thereby permitting solids to impinge upon the impeller face and to be thrown radially outwardly without chance of interference with the vanes or of producing damage to the vanes.

A further object of the invention is to provide in a centrifugal pump an impeller having a convex front face, wherein the centrifugal pumping vanes of the impeller are mutually spaced from a central area of the face of the impeller, and wherein the vanes form smooth junctures with the impeller face so that stringy material, for example, will not chance to hang up at vane, impeller face junctures but rather will slide outwardly over the leading edges of the vanes under the centrifugal force produced by the rotating impeller.

2

A further object of the invention is to provide in an impeller structure vane means on both faces of the impeller such that the pumping action is greater at the rear of the impeller than at the front, thereby insuring that solid material in the pump's liquid will not tend to accumulate along the rear face of the impeller.

A further object is to provide primary and secondary vane means on the front face of an impeller in such a manner that greatest pumping action is obtained proximate the periphery of the impeller, but with the face thereof being substantially unobstructed, thereby insuring a maximum throat or passageway for liquid passing between the impeller and the housing of the pump; for greatest efficiency and to reduce passageway obstruction, it is desired that the secondary vanes have girths or heights less than those of the primary vanes on the front face of the impeller.

A further object is to provide an impeller wherein the pumping action thereof is substantially obtained along the periphery of the impeller.

A further object is to provide vanes on both faces of a centrifugal pump impeller, with the vanes on the rear face being so disposed, and the character of the rear face being such that minimal protrusion of the rear vanes is obtained, thereby facilitating a close mounting of the rear of the impeller to the housing of the pump.

A further object of the invention is to provide a centrifugal pump impeller wherein the leading edges of the vanes thereof are prevented from protruding forwardly as their extremities are approached; rather, it is important that the vanes be normal to the impeller axis or, and preferably, sloped rearwardly so that solids build-up impeller vanes is avoided.

A further object is to provide a centrifugal pump wherein no clean-out facility is needed to clean the pump's impeller.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings in which:

FIGURE 1 is a vertical section taken along the line 45 1—1 in FIGURE 2 and shows the basic features of the invention; the circles indicated, a representative one of which is designated S in FIGURE 1, illustrate the largest possible mechanically-entrained solid objects which the centrifugal pump shown can accommodate.

FIGURE 2 is a front elevation of the centrifugal pump 50 of the present invention shown in FIGURE 1.

FIGURE 3 is a front elevation of the novel impeller of the invention.

FIGURE 4 is an elevation of the rear face of the 55 impeller shown in FIGURE 3.

FIGURE 5 is an enlarged, fragmentary section of a portion of the impeller of the present invention, showing the contour of vane junctures with the impeller base, and illustrates the important feature that the leading edges of 60 the front vanes of the impeller are at least parallel to and preferably slope rearwardly from an imaginary plane normal to the impeller face and intersecting the impeller's axis of rotation.

In FIGURE 1 housing structure 10 includes a conically 65 shaped housing bell 11 and housing back plate 12, this

structure being secured together by bolts 13 in cooperation with sealing gasket 14. The housing structure 10 is shown to include an inlet orifice 15 which, by reason of the inclusion of attachment flange 16, may be coupled to an external source of liquid. Exhaust orifice 17 is provided as a side aperture having communication with external conduit 18, the latter provided with attachment flange 19.

An impeller 20 of unique design is fixedly secured to impeller shaft 21 as by keying, a press fit, or other suitable means, and is journaled and sealed by packing gland 22, the latter being positioned in gland mounting portion 23 of the housing structure 10 and being secured and placed by packing retainer nut 24 which, upon positioning, is retained in place by set screw 25.

Essential limitations of the impeller are that it have a convex front face 26 and that it be provided with plural vanes 27 which, in a preferred form of the invention, comprises respective sets of vanes 27A and 27B. The several radial vanes 27 (sets 27A and 27B) are mutually spaced with respect to each other, see FIG. 3, and are preferably regularly spaced as shown. The vanes 27B are primary vanes which preferably extend to the periphery 28 of base 29 of the over-all impeller 20. Vanes 27A are auxiliary vanes which add to the centrifugal force produced by vanes 27B at the impeller periphery and, hence, to the pumping action of the impeller. It is to be noted in connection with the drawings that the secondary vanes 27A, in addition to being shorter than primary vanes 27B, also are reduced in height (i.e. width) when compared, point by point along concentric circles, with primary vanes 27B. See FIGURE 1. This is for the purpose of supplying flow paths for entrained solids which are relatively unobstructed, save for the slight protrusions of the upstanding secondary vanes 27A and the widely spaced, primary vanes 27B.

It is also noticed that the vanes 27 are mutually spaced apart not only among themselves but also from the center C of the impeller base 29. This provides a certain solids-impact area 30 of general disc form which receives impact forces thereon as produced by entrained solids impinging upon this central area 30; however, the leading edges of the vanes are spared this impact and the damage and/or wear which might be caused thereby.

Important note must be taken of the junctures 31 between blades 27 and the front face 26 of impeller base 29, see FIGURE 5. If we consider a plane which is normal to the plane of the paper, say, imaginary plane 33 intersecting axis 32 of shaft 21 (and rectilinearly related axis 33 of the impeller 20), then it is seen that the face 26, in being convex, gradually "falls away" from imaginary plane 33 as farther distances from the center C are reached.

Consider a secondary one of (here) coplanar imaginary planes 37 (see again FIGURE 5) which is normal to the plane of the paper and parallel to plane 33 and, further, which intersects the juncture of the leading edge 38, of a particular radial vane 27B (or 27A) with front face 26. Now if there is drawn a line 38' to juncture 31 tangent to face 26, which tangent line 38' is in the same plane as the proximate portion 40 of the leading edge 38 of vane 27B (or 27A), then the juncture angle A is seen to be greater than juncture angle B, that is, the angle between normal plane 37 and tangent line 38' in the plane of the paper. It is essential that juncture angle A be equal to or, and preferably, greater than juncture angle B. This is so that stringy sewage matter, for example, which may be present in the liquid source will not tend to pile up at juncture 31, but rather, will easily slide down the leading edge 38 of any of the plural vanes 27 (that is, 27A or 27B). It will be understood that, as seen in FIGURE 1, the limitation for juncture angle of the leading edges of the vanes will apply to all blades wherever situated on the front face of the impeller.

The impeller 20 itself has been described as having a

convex front face, which is convex toward intake orifice 15. Not considering the several vanes for the moment, it will be understood that the impeller 20 is preferably a geometric object of revolution the front face 26 of which may be thought of as being generated by circular, elliptical, paraboloid, or hyperboloid line segment generated about the axis 32 and rectilinear axis 33, the two axes coinciding in being the axes of impeller shaft 21 and impeller 20, respectively. Other types of line segments generated 360° about axes 33 and 32 may also be used such as a compound curve, for example, provided, however, that the over-all front face contour is in a general convex configuration, that is, all surface normals N to face 26 do not diverge.

In a preferred form of the invention it will be seen that the impeller 20 includes a concave rear face 34 upstanding from which are plural vane means 35 comprising a plurality of rearwardly facing, upstanding vanes 36; this construction insures that the impeller 20 might be placed as close as possible to housing back plate 12. Thus, it is seen to be desirable that the several rearwardly facing upstanding vanes 36 be contained within the general dish-configured concavity 37 as is formed the rear face 34 and outer periphery 28 of the impeller 20 proper. These vanes 36 may be relieved at 40 in a regular manner as is necessary to accommodate clearance for gland mounting portion 23 of the housing backplate 12. Of special importance in the invention is that the pumping action of the rear vanes 36 be greater than the pumping action of the vanes 27 (27A and 27B) upstanding from the front face 26 of the impeller 20. This is to assure that there will be no leakage problem whatever at the packing plant 22 and, further, and more important, so that gritty material in the fluid medium being pumped will not tend to work its way up into the interior of the structure as in a direction R. Through experimentation the inventor has discovered that when the pumping action of the rear vane 36 exceeds that of the plural front vanes 27, then the packing gland 22 can even be removed while the pump is being operated without any leakage being present. Hence, there is assured an important feature of the invention wherein, in operation, the apparatus keeps the pumped media from collecting rearwardly of the impeller 20.

Increased pumping action of the rear vane means 35 over the front plural vanes 27 may be obtained by appropriately designing the individual vanes relative to the respective impeller faces 26 and 34. It is well known in the art that pumping action increases as vane area increases and as the distance of the vane from the impeller's center of rotation is increased. In the example given in FIGURE 1, increased vane area of the rearwardly facing vane means 35 is relied upon to produce a pumping effect greater than that of the front vanes 27.

The pump shown in FIGURE 1 operates as follows. Motor M is directly coupled to impeller shaft 21 to rotate the same. A liquid-carried, mechanically-entrained solid enters intake orifice 15; the liquid phase is automatically directed along a generally conically-configured, pumped media passageway 41 in the direction of arrows L. Since the front face 26 being convex towards the source of the fluid, fluid turbulence at the central area 30 of the front face is reduced to a minimum. This is desirable from an efficiency point of view and for obtained desirable flow patterns.

Entrained solids impinge upon the solids-impact area 30, see FIGURE 3, and friction and impact with the revolving face 26 urges the solids S upwardly and directly along the front face. Liquid flow tends to keep the solids against the front face as they proceed outwardly therealong. Now it is desired that the pump accommodate all types of liquid media including that wherein solids such as sewage, stringy matter, and solid particles as in slurries, may be accommodated. It is desired that the solids have as little contact with the centrifugal impeller vanes 27A and 27B as possible. Hence, the solids, by

virtue of liquid pressure intending to keep them against the front face 26, will proceed outwardly along the impeller base 29 at the front face 26 thereon and between the widely spaced vanes 27B. The secondary vanes 27A provide increased centrifugal action at the periphery 28 while not impeding the travel of the solids. In this regard it is eminently desirable to have the girth or height of the vanes restricted as shown in FIGURE 1 so that a generous flow passageway will be presented between the leading edges 38 of vane means 27 and housing 10 and also between adjacent ones of the primary vanes 27B. In view of the fact that there is an ample, conically-shaped, fluid-flow passageway defined by the leading edges of blades 27B and the interior surface 45 of housing bell 11, solid matter will not tend to be impeded in its outward travel toward an annular discharge chamber 46 by the existence of the vanes. Further, it is important to note that the contour areas at junctures 31 (see FIGURE 5) of the vanes, both primary and secondary, with the impeller face 26 are such that stringy solid matter, for example, will not tend to cling to or be caught by these junctures. Hence, it is important that the leading edges 38 of the vanes 27B and 27A be such that they be coplanar with or, and preferably, sloped rearwardly with respect to imaginary planes (e.g. 37), parallel to the primary imaginary plane 33 in FIGURE 5, which intersect and are normal to axes 32 and 33. Hence, stringy solid matter will tend to slide off the leading edges of the vanes 27 (27A and 27B) under the centrifugal action of the pump without chancing any accumulation whatever at the impeller area. Hence, clean-out holes and traps in the design need not be incorporated. Once the liquids and the solids reach the annular discharge chamber at 46, the same are intimately re-combined again, and are urged out of exhaust orifice 17 and hence out conduit 18 as a pump fluid.

It will be noted that the centrifugal pump may be utilized for pumping any type of liquid; however, it is particularly suited for liquids having mechanically entrained solids such as sewage, slurries, mud fluids for drilling, and so forth.

There has been discussed previously the action of the rear vanes 35 in keeping substantially all fluid flow in front of the impeller and permitting the accumulation of no gritty material or other solids rearwardly of the impeller. Indeed, by virtue of the fact that the pumping action of the rear vanes 35 exceeds that of the front vanes 27, no fluid whatever will accumulate rearwardly of the impeller so long as the pump is operating.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. In a centrifugal pump including housing structure defining an interior cavity and including a central intake orifice and a side exhaust orifice, and a shaft sealingly journalled to and extending within said housing structure and nominally axially disposed in line with and facing said intake orifice; an improvement comprising an impeller revolvably disposed in said housing structure and including a base fixedly secured to said shaft, said base having a continuous, convex front face which is spaced from and faces said intake orifice, said shaft having an axis of rotation passing centrally through said front face, said impeller also including plural, radially extending vanes affixed to said base and upstanding from said front face, said vanes being mutually spaced from each other and from the center of said front face, said vanes having leading edges terminating short of a primary imaginary plane normal to and intersecting said shaft axis at its

intersection with said front face, said leading edges of said vanes having their respective portions proximate said front face joining said front face in respective contours, to form juncture angles, that is, angles between said proximate portions of respective ones of said leading edges of said vanes and tangents to said front face at said contours which respectively lie in the same planes as said proximate portions of respective ones of said leading edges of said vanes, said juncture angles of said leading edges with said front face being not less in magnitude than juncture angles between said front face and respective, secondary imaginary planes parallel to said primary imaginary plane and respectively intersecting said front face at respective leading edges' junctures therewith, and said housing structure and said impeller being so constructed and arranged to provide an annular discharge chamber circumscribing said impeller and communicating with said discharge orifice and also to provide an annular, conical, pumped-media passageway interconnecting said intake aperture with said discharge chamber and disposed between said leading edges of said vanes and said housing structure.

2. Structure according to claim 1 wherein said vanes extend to the periphery of said base.

3. Structure according to claim 1 wherein some of said plural vanes are radially shorter than remaining vanes and wherein those of said plural vanes which are radially shorter are also reduced in height when compared, point by point along concentric circles with said remaining vanes.

4. Structure according to claim 2 wherein some of said plural vanes are radially shorter than remaining vanes, and wherein those of said plural vanes which are radially shorter are also reduced in girth relative to that of the remaining vanes.

5. In a centrifugal pump including housing structure defining an interior cavity and including a central intake orifice and a side exhaust orifice, and a shaft sealingly journalled to and extending within said housing structure and nominally axially disposed in line with and facing said intake orifice; an improvement comprising an impeller revolvably disposed in said housing structure and including a base fixedly secured to said shaft, said base having a continuous, convex front face which is spaced from and faces said intake orifice, said shaft having an axis of rotation passing centrally through said front face, said impeller also including plural, radially extending vanes affixed to said base and upstanding from said front face, said vanes being mutually spaced from each other and from the center of said front face, said vanes having leading edges terminating short of a primary imaginary plane normal to and intersecting said shaft axis at its intersection with said front face, said leading edges of said vanes having their respective portions proximate said front face joining said front face in respective contours to form juncture angles, that is, angles between said proximate portions of respective ones of said leading edges of said vanes and tangents to said front face at said contours which respectively lie in the same planes as said proximate portions of respective ones of said leading edges of said vanes, said juncture angles of said leading edges with said front face being not greater in magnitude than juncture angles between said front face and respective, secondary imaginary planes parallel to and spaced rearwardly from said primary imaginary plane and respectively intersecting said front face at respective leading edges' junctures therewith, and said housing structure and said impeller being so constructed and arranged to provide an annular discharge chamber circumscribing said impeller and communicating with said discharge orifice and also to provide an annular, conical, pumped-media passageway interconnecting said intake aperture with said discharge chamber and disposed between said leading edges of said vanes and said housing structure.

6. In a centrifugal pump including housing structure defining an interior cavity and including a central intake orifice and a side exhaust orifice, and a shaft sealingly journaled to and extending within said housing structure and nominally axially disposed in line with and facing said intake orifice; an improvement comprising an impeller revolvably disposed in said housing structure and including a base fixedly secured to said shaft, said base having a continuous, convex front face which is spaced from and faces said intake orifice, said shaft having an axis of rotation passing centrally through said front face, said impeller also including plural, radially extending vanes affixed to said base and upstanding from said front face, said vanes being mutually spaced from each other and from the center of said front face, said vanes having leading edges sloped rearwardly with respect to the direction in which said front face is facing, said front face being free of said vanes in a central region the size of which at least

5 equals the size of said central intake orifice, said central region being nominally in registry with said central intake orifice.
